CLAIM

The ornamental design for a tie-down bracket for a vehicle mounted article carrier, as shown and described.

DESCRIPTION

FIG. 1 is a top plan view of a tie-down bracket for a vehicle mounted article carrier showing my new design;

FIG. 2 is a rear elevational view thereof;

FIG. 3 is a bottom plan view thereof;

FIG. 4 is a front elevational view thereof;

FIG. 5 is a side elevational view thereof, and FIG. 6 is a side elevational view thereof as seen from the side opposite that of FIG. 5.
